BLOWPIPE

Wilgot J. Jacobsson, Scotch Plains, and Samuel R. Oldham, Elizabeth, N. J., assignors to Oxweld Acetylene Company, a corporation of West Virginia

Application April 17, 1937, Serial No. 137,420

6 Claims. (Cl. 153—27.4)

This invention relates to a blowpipe, and more particularly to a blowpipe which is adapted to use either low or medium pressure fuel gas efficiently and without danger of flashbacks.

6 Fuel gas (as acetylene) may be available at different places or at different times as low pressure gas or as medium pressure gas. It is therefore desirable for a user to have available a single blowpipe which may be used efficiently with fuel 10 gas at either pressure. Obviously, it is more convenient to use a single blowpipe for any fuel gas pressure than it is to have available a plurality of blowpipes, one for each gas pressure which may be supplied. Clearly also, it is less expensive to 15 purchase, maintain, and accommodate one blowpipe than two or more.

In the past, blowpipes have been constructed so that they would not flashback at a given fuel gas pressure. However, increasing or decreasing 20 that pressure to any considerable extent has materially altered the flashback resistance of the blowpipe. For this reason, it has not been possible to use the same blowpipe for both low pressure and medium pressure fuel gas unless nozzles 25 or other parts of the blowpipe were changed.

One object of the invention is therefore to provide a single blowpipe for use with fuel gas at different pressures. Another object is the provision of such a blowpipe wherein flashback resistance will be maintained over a wide range of fuel gas pressures. A further object is the provision 30 of such a blowpipe in simple, rugged, and easily maintained form.

Other objects and novel features of the invention will be apparent from the following description taken with the accompanying drawing, in which:

Fig. 1 is a view partly in longitudinal section and partly in side elevation, showing a blowpipe 40 constructed in accordance with the invention;

Fig. 2 is a fragmental plan view of a part of the blowpipe as seen from the line II—II in Fig. 1;

Fig. 3 is a cross section of the blowpipe taken on the line III—III of Fig. 2;

45 Fig. 4 is a cross section of a part of the blowpipe taken on the line IV—IV of Fig. 1; and

Fig. 5 is a side elevation of the mixing assembly of the blowpipe.

According to the present invention, a blowpipe 50 is provided having an improved preheat gas mixing assembly whereby flashbacks are prevented, whether low or medium pressure fuel gas is used. The preheat gas mixing assembly includes an injecting nozzle, an elongated conduit, and a rear block, all rigidly connected together in coaxial

series alignment and disposed within an elongated cavity in the blowpipe, to provide a mixing chamber, and two concentric gas passages terminating in the mixing chamber. A special mixing throat and expansion passage are also provided.

For convenience, the words "oxygen" and "acetylene" will be used in this specification to denote respectively any appropriate cutting and combustion-supporting gas and any appropriate fuel gas.

In the embodiment which is illustrated in the drawings, there is shown a cutting blowpipe comprising a head H connected, by means of a cutting oxygen tube C and a combustible mixture conduit M, to a valve block B to which oxygen and acetylene are supplied through nipples O and A respectively. A tip T is fastened in the head H by means of a hollow attaching nut N, in the usual manner.

Oxygen enters the valve block B from the nipple O through a passage 10, whence it passes to an annular chamber 11, from which its passage to the cutting oxygen tube C and to the combustion mixture conduit M is regulated by valves 12 and 13 respectively.

Thus the combustion-supporting oxygen passes from the annular chamber 11 to a duct 14 in the valve block, the far end of which provides a valve seat and is closed by the valve 13. This valve is carried by a threaded valve stem 15 operated by a handle 16 to move against the valve seat associated with the duct 14 or to be retracted from this seat into a valve chamber 17 which is formed in the valve block B. A cross passage 18 connects the valve chamber 17 with an opening 19 in the valve block B. Accordingly, by turning the handle 16 combustion-supporting oxygen may be permitted to flow into the valve chamber 17 and thence through the cross passage 18 to the opening 19 in the valve block.

The opening 19 extends forwardly from the valve block B to a large conduit 20 extending forwardly in continuation thereof, which is gas-tightly connected to the valve block as by silver-soldering at 21, and which extends forwardly to the mixture conduit M (later to be described) to which its forward end is gas-tightly connected as by silver-soldering at 22. Thus the opening 19 in the valve block and the large conduit 20 together form an elongated cavity extending continuously through the valve block B to the mixture conduit M.

The unitary nozzle assembly X is disposed within, and has longitudinally slidably engagement with the walls of, the elongated cavity 50

formed by the opening 19 in the valve block B and its extension within the large conduit 20, and comprises a nozzle 23, an elongated conduit 24, and a rear block 25, all rigidly connected together in coaxial series alignment and removably disposed in the elongated cavity. The nozzle has a passage 26 extending therethrough, and the rear block has a passage 27 extending therethrough, each passage communicating with and 10 being a continuation of the passage through the conduit 24. An annular shoulder 28 adjacent the forward end of the rear block 25 contacts a corresponding internal shoulder 29 on the wall of the opening 19 and limits the axial or longitudinal position of the unitary nozzle assembly X within the elongated cavity. Thus the nozzle 23 is properly spaced within the elongated cavity to provide a mixing chamber 30 therein, and at the same time the assembly is gas-tightly connected at its rear end in the elongated cavity. Furthermore, the rear end of the mixture conduit M presents a concave opening providing a conical or tapered wall 31 which is complementary to the forward end of the nozzle 23. The 25 length of the assembly ahead of the annular shoulder 28 is such that the smooth tapered forward end of the nozzle is accurately and closely spaced adjacent to the conical wall 31 by a distance insufficient to form a substantial enlargement 30 wherein backfires might lodge to become flashbacks when the nozzle assembly is in place. Thus an acetylene metering clearance is provided at the front end of the nozzle next to the mixture conduit. This metering clearance is of importance 35 in feeding to the mixing chamber 30 the proper amount of acetylene whether that gas be at low pressure, or medium pressure.

Alignment of the assembly X within the elongated cavity is fixed by means of a series of 40 longitudinally extending widely spaced radial projections 32 on the nozzle 23, the total cross sectional area of the spaces between projections being greater than the total cross sectional area of the projections themselves, and by means of 45 the rear block 25, the diameter of which is designed to be equal to the internal diameter of the opening 19 within the valve block B. The projections 32 and the rear block 25 are each adapted to have longitudinally slidably engagement 50 with the walls of the elongated cavity to facilitate insertion and removal of the nozzle assembly. The rear block is of greater diameter than the nozzle or the elongated conduit. The smallest diameter of the elongated cavity is, of 55 course, sufficient to permit passage of the nozzle 23 and of parts of the unitary assembly ahead of the annular shoulder 29 on the rear block 25.

The opening 19 through the valve block B is internally threaded at its rear end, and a locking 60 screw 33 may be screwed into the opening to bear upon the rear face of the rear block 25 and lock the unitary assembly X in place. The locking screw has a central passage 34 therethrough resembling a keyhole through which gas may 65 pass, and into which a tool may be inserted to turn the locking screw in the internal threads of the opening. The passage 27 through the rear block 25 is disposed in substantial alignment 70 with the passage 34 through the locking screw and is internally threaded in order that an instrument may be inserted therein for withdrawing the unitary assembly from the elongated cavity. Such threads may be designed so that an ordinary long machine screw will serve this purpose. 75

A threaded plug 35 having an external kerf in its head is screwed into the end of the opening 19 in the valve block B to close the same. The threaded stem portion of the plug is designed to leave a space between the plug and the locking screw 33 when the latter is in position against the rear block 25. Thus a chamber 36 is formed in the opening 19 between the locking screw and the plug. The cross passage 18 is designed to terminate in the chamber 36. Accordingly, combustion-supporting oxygen flowing through the cross passage 18 when the valve 13 is open enters the chamber 36, passes through the central passage 34 in the locking screw 33, passes thence through the passage 27 in the rear block 25 to the elongated conduit 24, and from the conduit 24 through the axial passage 26 in the nozzle 23 to the mixing chamber 30.

Acetylene entering the blowpipe through the nipple A flows through an acetylene passage 37 20 in the valve block B to a point ahead of the rear block 25 in the opening 19. A valve (not shown) operated by a handle 38 controls the flow of acetylene through the passage 37 in well-known manner. From the forward end of the passage 37, acetylene flows through the large conduit 20 in the annular space surrounding the elongated conduit 24 to the space surrounding the nozzle 23, which space is free of obstructions or enlargements. Thence the acetylene passes through 30 the metering clearance at the front end of the nozzle to the mixing chamber 30, by the combined action of its own pressure and the aspirating effect of the combustion-supporting oxygen stream issuing from the end of the nozzle. 35

The diameter of the smooth-walled cylindrical portion of the nozzle 23, which merges at its front with the tapered nozzle end, and the distance by which the narrow projections 32 extend beyond its periphery are designed to give 40 the required uniform spacing or clearance between the nozzle and the elongated cavity, thereby producing a further metering action with respect to the flow of acetylene through the blowpipe. Similarly, the forward end of the passage 45 26 through the nozzle is constricted to provide a metering orifice 39 for the combustion-supporting oxygen. The elongated passage back of each metering point, and the large volume of gas contained in each passage, provides a cushion 50 back of each constriction which tends either to smother or rapidly to burn out backfires in a large volume of one of the gases, and to drive the burning or burned mixture forward again. The small angle which the end of the nozzle 23 55 makes with its major axis and the wide spacing of the projections 32 afford a minimum obstruction to the passage of fuel gas along the outside of the nozzle. This small angle also facilitates passage of backfires into the large volume of 60 acetylene surrounding the elongated conduit 24, where the backfires are smothered. Any portion of a backfire which enters the passage 23 and passes to conduit 24 is rapidly and completely 65 burned out by the excess of oxygen contained therein.

Clearly, better results are obtained with low pressure acetylene when smaller clearances between the nozzle 23 and the wall of the elongated cavity are provided, and with medium pressure acetylene when larger clearances exist between the nozzle and the wall of the elongated cavity. However, the described construction is such that this difference is minimized. The actual clearance is a compromise between the two clearances. 75

Furthermore, it is possible to throttle down the pressure of medium pressure acetylene to some extent by means of the acetylene valve.

Combustion-supporting oxygen from the nozzle 23 and acetylene entering the mixing chamber from the space surrounding the nozzle are projected into a mixing throat 40 beyond the end of the nozzle and coaxial therewith. From the mixing throat 40, the combustible gas mixture 10 enters the small end of a diverging expansion passage 41, and expands gradually from the mixing throat to the forward end of the mixture conduit M. A short passage 42 connects the end of the expansion passage with a tip cavity 43 in 15 the blowpipe head at a point from which the combustible gas mixture may pass conveniently through the tip T.

It is preferred to make the mixture conduit M with exceedingly thick walls surrounding the mixing throat 40 and the expansion passage 41. It is also desirable to make these walls of a metal having high heat conductivity. Thus, should ignited gases enter either passage, heat will be rapidly extracted therefrom by a considerable mass 25 of metal. Furthermore, this mass and character of metal will prevent overheating and burning out of the blowpipe.

The cutting oxygen valve 12 which controls the passage of cutting oxygen from the annular chamber 11 to the cutting oxygen tube C is especially designed to permit convenient control, particularly in starting a cut. Accordingly, the valve 12 is constructed in conical form in order that it may open gradually. Any known or convenient valve-operating construction may be employed: for instance, a lever-operated, spring-closed mechanism. It is also to be noted that the large volume of oxygen contained in the elongated conduit 24 tends to cushion the effect upon 40 the mixing point of any change in pressure adjacent the valve 12.

From the foregoing, it will be apparent that a simple, rugged, and easily maintained blowpipe has been provided in which flashback resistance 45 is effectively maintained over a wide range of fuel gas pressures.

The form of the invention here described and illustrated in the accompanying drawing is disclosed merely to indicate how the invention may be applied. Other forms, differing in detail but not in principle from that here shown and described, will, of course, suggest themselves to those skilled in the art.

We claim:

1. A blowpipe having an elongated cavity therein terminating in a wall surrounding the entrance to a mixing throat; a nozzle assembly in the elongated cavity in said blowpipe, said assembly comprising a nozzle, an elongated conduit, and a rear block, all rigidly connected together in coaxial series alignment and disposed within the elongated cavity with the forward end of said nozzle closely adjacent the wall in which the elongated cavity terminates, and with said nozzle spaced from the internal wall of said cavity to form a passage therebetween; the space within the elongated cavity and surrounding said elongated conduit behind said nozzle being adapted to act as a chamber to receive and extinguish 65 backfires, and the passage between said nozzle and the wall of said cavity being adapted to permit backfires to pass freely therethrough into the chamber surrounding said conduit.

2. For use with a blowpipe having an elongated cavity therein, a unitary assembly com-

prising a nozzle, an elongated conduit, and a rear block, said nozzle, said conduit and said rear block all being rigidly connected together in coaxial series alignment; said nozzle having a smooth tapered front end and a smooth-walled cylindrical portion merging at the front with said tapered end and extending to the rear end of said nozzle; and a series of longitudinally extending widely spaced projections on the periphery of said nozzle, the total cross sectional area of the spaces between said projections being greater than the total cross sectional area of said projections; said nozzle and said rear block having passages therethrough in communication with the passage through said conduit, and said projections and said rear block serving to align the assembly within the elongated cavity in the blowpipe.

3. In a blowpipe, a mixture conduit having therein a mixing throat and an elongated gradually expanding passage in continuation of the mixing throat; a valve block having an opening therein; and a large tube gas-tightly sealed about the end of the mixing throat in said mixture conduit and about the end of the opening in 20 said valve block, said opening and the passage through said tube providing an elongated cavity in said blowpipe; in combination with a unitary assembly comprising a nozzle, an elongated conduit, and a rear block, all rigidly connected together in coaxial series alignment, said nozzle and said rear block having passages therethrough in communication with the passage through said elongated conduit; means for spacing said nozzle from the end of the mixing throat by a distance insufficient to form a substantial enlargement wherein backfires might lodge to become 30 flashback, said means comprising an annular shoulder on said rear block for seating against a shoulder in the opening in said valve block, and means for spacing said elongated conduit and said nozzle from said tube to provide a long annular gas chamber behind the nozzle, and a passage along the outside of said nozzle, said last named means comprising a series of longitudinally extending widely spaced projections associated with said nozzle, the space between said projections being sufficiently great to permit the free passage of a backfire through said passage between said projections and thence into said 40 chamber.

4. In a blowpipe having an elongated cavity therein terminating at its forward end in a tapered wall surrounding the entrance to a mixing throat; the combination comprising an elongated combustion-supporting gas conduit disposed within said cavity in spaced relation to the wall thereof providing around said conduit a long annular chamber adapted to contain a large volume of fuel gas; and a nozzle secured to the forward end of said conduit within said cavity, said nozzle having a tapered smooth forward end adjacent to said tapered wall and spaced therefrom, and having a smooth-walled cylindrical portion uniformly spaced throughout its length from the wall of said cavity, said cylindrical portion merging at its front with said tapered end, the external wall of said nozzle and the wall of said cavity providing therebetween a 65 continuous passage whereby backfires pass freely and directly back into said long annular chamber and are extinguished in the large volume of fuel gas contained therein, said passage being free of both obstructions to the passage of back- 70

55

60

65

70

75

fires and enlargements wherein backfires might lodge to become flashbacks.

5. In a blowpipe having an elongated cavity therein terminating at its forward end in a tapered wall surrounding the entrance to a mixing throat; the combination comprising an elongated combustion-supporting gas conduit disposed within said cavity in spaced relation to the wall thereof providing around said conduit a long annular chamber adapted to contain a large volume of fuel gas; a nozzle secured to the forward end of said conduit within said cavity, said nozzle having a tapered smooth forward end adjacent to said tapered wall and spaced therefrom, and having a smooth-walled cylindrical portion uniformly spaced throughout its length from the wall of said cavity, said cylindrical portion merging at its front with said tapered end and extending to the rear end of said nozzle, the external wall of said nozzle and the wall of said cavity providing therebetween a continuous passage whereby backfires pass freely and directly back into said long annular chamber and are extinguished in the large volume of fuel gas contained therein, said passage being free of both obstructions to the passage of backfires and enlargements wherein backfires might lodge to become flashbacks; and means accurately centering said nozzle in said cavity to maintain the uniform spacing thereof from said cavity wall, said means

comprising a plurality of narrow longitudinally extending lateral projections on the external wall of said nozzle contacting the wall of said cavity.

6. In a blowpipe having an elongated cavity therein terminating at its forward end in a tapered wall surrounding the entrance to a mixing throat; the combination comprising an elongated conduit disposed in said cavity with its external wall spaced from the wall of said cavity to provide a chamber around said conduit adapted to contain a large volume of gas; a nozzle on the forward end of said conduit within said cavity, said nozzle having a tapered smooth forward end adjacent to said tapered wall and spaced therefrom, and also having a cylindrical portion merging at its front with said tapered end; and a plurality of longitudinally extending widely spaced projections uniformly spacing the cylindrical portion of said nozzle throughout its length from the wall of said cavity to provide passage means along the outside of said nozzle, the total cross-sectional area of the spaces between said projections being greater than the total cross-sectional area of said projections whereby to permit the free rearward passage of backfires through said passage means between said projections and thence into said chamber.
